UNITED STATES PATENT OFFICE.

NORMAN E. WOODS, OF PATERSON, NEW JERSEY.

METHOD OF MAKING TWIST DRILLS.

Original application filed September 30, 1919, Serial No. 327,541. Patent No. 1,384,738, dated July 12, 1921. Divided and this application filed July 11, 1921. Serial No. 483,886.

To all whom it may concern:

Be it known that I, NORMAN E. Woods, a citizen of the United States, residing at Paterson, in the county of Passaic and State of New Jersey, have invented new and useful Improvements in Methods of Making Twist Drills, of which the following is a specification.

This invention relates to a new and improved method of making drills, particularly metal-boring drills of the twist type; and the present application is a division in part of my prior application filed September 30, 1919, Ser. No. 327,541, eventually in Patent No. 1,384,738, dated July 12, 1921, covering a drill structure made in accordance with this method.

Drills of the twist type, as at present constructed, are defective in that each cutting lip cuts a single heavy chip, which chips, in addition to throwing heavy strain upon the drill, tend to lodge in the flutes and cause friction and loss of power. The packing of these chips in the flutes also tends to obstruct the flow of the lubricant to the cutters, with a further increase of friction, loss of power, and generation of heat and the burning and deterioration of the metal of the drill at the point. Moreover, as the point has no cutting action, but acts merely to center the drill and force the metal beneath it from the center toward the cutting lips, the drill, as it feeds into the work, causes a compression of the metal from the center toward the periphery of the drill. This compression greatly increases the weight of a chip from its normal weight under a fixed feed per revolution until it is compressed to a number of times its normal thickness of cut per revolution. Such compression is more perceptible, and adds still greater resistance to the progress of the drill, when lubricant does not meet the point and the chip is softened in heating up by the friction of the cutting edge and the chisel point. Hence the drill is liable to break under the heavy strains and to become quickly dull, requiring frequent sharpening, and comparatively great power is required to feed the drill in its work. Drills provided with flutes extending to points at their heel edges also tend to further retard the clearance of the chips and cannot be uniformly tem-

pered, owing to wide variations in the thickness of the metal at different portions thereof.

The general object of my invention is to provide a method of making a drill which overcomes the objections above noted to drills of ordinary construction, and which, therefore, is stronger and capable of resisting greater strains and is less liable to fracture than twist drills of the types in common use, and which will more efficiently lubricate the work and allow freer clearance of the chips and cut faster with less resistance than any ordinary type of drill.

A further object of the invention is to provide a method of manufacture which simplifies the operation of making a drill having auxiliary grooves and cutting edges of a particular character for securing the desired results.

The invention consists of the features of construction, combination and arrangement of parts, hereinafter fully described and claimed, reference being had to the accompanying drawings, in which:—

Figure 1 is a view in side elevation of a blank from which the drill is made.

Figure 2 is a cross-section through the blank.

Figure 3 is a view in side elevation of a twist drill embodying my invention.

Figure 4 is a plain view of the cutting end of the drill.

Figure 5 is a cross-section through the drill and an object being bored thereby.

Figure 6 is a diagrammatic plan view illustrating the cutting action of the lips.

Figure 7 is a diagrammatic view in elevation of the same.

Figure 8 is a view showing the division of the cuts and the chips formed by the cutting lips.

Figure 9 is a cross-section through a drill blank, showing a slight modification in the form of a groove.

Figure 10 is a similar view of the drill as formed from the blank shown in Figure 9.

In order that a clear understanding of my invention may be obtained, I will first describe the construction of the drill, and then describe the method of making it.

Referring to Figures 1 to 8, inclusive, of the drawings, 1 designates the body or

shank of the drill, which is of the ordinary twist form, 2 and 3 the portions of the body forming the spiral cutting blades, 4 the central web connecting the inner edges 5 of the blades, 5 and 6 the flutes formed by and between the twisted blades, 7 the chisel cutting point at the outer end of the web, and 8 and 9 the cutting lips at the outer edges of the blades 2 and 3.

10 In carrying my invention into practice, I provide the face of each cutter blade 2 and 3 with a longitudinally extending channel or groove, the face of the blade 2 being provided with a groove or channel 10 and the 15 face of the blade 3 with a groove or channel 11. These grooves or channels preferably extend throughout the length of the blades and intersect the cutting lips 8 and 9, thereby separating the respective cutting 20 lips into a plurality of cutting portions. As shown, the groove 10 separates the lip 8 into aligned cutting portions 10^a and 10^b, while the groove 11 separates the lip 9 into aligned cutting portions 11^a and 11^b.

25 It will be observed that the grooves 10 and 11 of the cutters are staggered with relation to each other, that is, arranged at different distances from the drill center, the lip 8 thus being separated by its groove 10 30 into a short straight inner cutting member 10^a and relatively longer straight outer cutting member 10^b, while the lip 9, on the contrary, is separated by its groove 11 into a relatively long straight inner cutting member 11^a and a relatively short straight outer cutting member 11^b. Each cutting lip, therefore, instead of forming a chip coextensive in width therewith, produces a chip which is divided into relatively narrow and 40 wider sections, both materially narrower than the width of the lip, leaving an uncut ridge of a depth corresponding to the groove therebetween. This is clearly shown in Figures 6, 7 and 8, wherein a, a' and a² respectively designate the chip sections and ridge formed by the cutting lip 8 and b, b' and b² the chip sections and ridge formed by the cutting lip 9. By the division of the chips 45 in the manner stated the objections incident to ordinary drills, in which each lip forms a single wide chip, are avoided, in that the sectional chip may be cut with greater freedom and ease and with a reduction of strain and friction, and the sections of the chip 50 have greater ease of clearance, in that they will pass into and upwardly through the flutes in a free and easy manner, and without the tendency to bind therein and create great resistance and friction, as with chips 55 of normal size. Accordingly, the working strains upon the drill will be materially reduced and a drill of a given size, and rotated at a given speed, may be operated to 60 cut at greater speed than an ordinary drill 65 and with less driving power. Furthermore,

owing to the reduction of strain, the web 4 may be thinned or reduced in thickness by at least 15° less than the standard proportion, with the effect of narrowing the point 7, and without weakening the drill, with the 70 additional advantageous result of diminishing to a great extent the compression of the chips by the point of the drill, friction and undue heating of the drill point and chips being also thus reduced to a further degree. 75

In practice, the grooves 10 and 11 of the cutters are preferably made deepest at the points where they intersect the lips 8 and 9 and then gradually diminish in depth toward the drill shank, and the groove 10 of 80 one of the cutters, is preferably made of less depth than the groove, as the groove 11, of the other cutter, with the result of further reducing the sizes (widths) of the chips made by one cutter with respect to those 85 made by the other, so that chips of different sizes will be formed which will more readily intermingle in their discharge to secure easy and rapid clearance. Another purpose of making the groove 11 deeper 90 than the groove 10 is to allow greater clearance owing to its greater distance from the drill center and its greater ratio of cutting speed due to the larger circle in which it travels, also, by such clearance, to 95 prevent burning of the cutting edge at the outer wall of said groove 11 by high friction due to its speed. This deeper groove 11 also further promotes free supply of lubricant to the cutting surfaces. It will be 100 understood that by the arrangement of the grooves 10 and 11 in staggered relation, or at different distances from the center point 7, provision is made so that a cutting portion of each lip will remove the ridge left 105 standing by the other lip, the cutting portion 10^b of the lip 8 removing the ridge b² formed by the lip 9, while the cutting portion 11^a of the lip 9 will remove the ridge a² formed by the lip 8, thus producing an 110 absolutely smooth and finished bore. By reducing the thickness of the web 4, it will further be evident that the depth of the flutes or clearance channels 5 and 6 will be increased, ensuring still further reduction 115 of friction and any tendency of the chips to pack or bind therein. It will, of course, be understood that the grooves 10 and 11 also provide flow channels for the passage 120 of lubricant to the cutting surfaces. 120

The grooves may be forged during the process of manufacture of cast in the drill in the process of making a cast drill, or may be milled or otherwise formed in a drill blank prior to the operation of twisting the 125 same, my invention being directed to a form of groove resulting from the change produced by twisting of the drill blank from a groove of primarily different form. Figures 1 and 2 show a drill blank 1^a having 130

grooves 10^a and 11^a forged, cast or milled therein, from which blank the complete drill shown in Figures 3 to 8, inclusive, is made. As shown in Figure 2, the grooves 10^a and 11^a are primarily of half-round or semi-circular form as made in the drill blank, and the result of twisting the drill blank to form the complete drill will be to impart to each groove the semi-elliptical form or parabolically curved form shown in Figures 3, 4 and 5. This change in formation occurs, as stated, as a result of the twisting of the drill blank, and the result of the formation of a groove of semi-elliptical shape is to secure certain desirable and important advantages. Such form of the groove, which is deepest toward the periphery of the drill and shallowest at its side nearest the center of the drill, results in the formation of a groove which allows freer clearance of the chips and also of the production of an overhanging cutting edge or point *c* at the intersection of the wider end of the groove with the lip, which edge serves to make a clean cut and prevent any drag and the formation of any fins or ragged surfaces on the chips liable to cause friction and retard the clearance of the chips. Also said cutting edge tends to force the chips at right angles to the direction of rotation, thus centering them in the flutes and still further facilitating the clearance action.

In Figures 9 and 10 I have shown a slight modification in the initial and final form of the grooves. By reference to Figure 9, it will be observed that while the groove 10^a in the drill blanks is substantially of half-round form, like the groove 10^a of Figure 2, the groove 11^b of the drill blank in Figure 9 is much deeper, being substantially of semi-elliptical form with its major axis arranged at right angles to the cutting edges of the drill. When this blank is twisted to produce the drill shown in Figure 10, the form of the shallow groove 10^b is varied to accord substantially with the groove 11^b of Figure 4, but the change in the form of the groove 11^b is not so pronounced, said groove 11^b substantially preserving its original general U-shaped contour. However, owing to the twist of the drill, this groove 11^b is given a change of shape, its major axis being varied from a straight line position at right angles to the cutting lips to a curved line position in which it is eccentric to the axis of the drill, thus giving the same cutting and clearance effect as the shallower grooves with a much deeper clearance. It will be observed that while in the two constructions shown the grooves differ initially in relative depth, the general shape of the grooves initially formed in the two blanks is the same, that is to say, that U-shaped grooves are provided, which may vary between a half-round and semi-elliptical form.

cal form, with a corresponding change in the form of the grooves produced in the finished articles.

It will be obvious that, in addition to the functional advantages stated, the grooves 10 and 11 also serve to form a pilot or leader for the drill, which guides the drill or causes it to run more accurately or centrally than a drill of ordinary type. 70

While I have specified the use of a single groove in each drill lip, which is sufficient in drills up to a certain diameter, it is to be understood that any desired or required number of grooves may be formed in each drill lip as may be found most advantageous in drills of different diameters. Also while I have shown and described the use of grooves of certain form in the drill lips, I do not wish to be strictly confined thereto, except when specifically set forth in certain claims; as while such form of grooves has been found to be of desirable and special advantage, especially in their use in large drills which cut coarse chips, grooves of other equivalent form, when employed in connection with the other stated improvements of my invention, may be used in drills of small size which cut comparatively small chips.

In twist drills of ordinary construction 95 the heel edges of the cutting members 2 and 3 generally extend to points or flukes, with the result that the flutes 5 and 6 are contracted thereby and the cutting members made of such irregular form and varying 100 widths as to make it impossible to temper the drill evenly or in such manner to be free from flaws. I overcome this objection by rounding the heel ends of the cutting members, as indicated at 12, thus widening the flutes 5 and 6 and removing an excess of metal adding to the difficulty in tempering the drill evenly. By this construction an added advantage is obtained, in that in the upward flow of the masses of chips through the flutes pockets or channels 12' are produced between the same and the surfaces 12, affording additional channels for the flow of lubricant to the cutting surfaces. 110

Having thus fully described my invention, I claim: 115

1. The method of making a twist drill which consists in providing a drill blank having grooves of a predetermined substantially circular cross-sectional form extending lengthwise of its blades and intersecting the cutting lips thereof, and then twisting the blank to impart the desired spiral form to the blades and to simultaneously distort the walls of the grooves so as to produce grooves which are comparatively shallow at their sides nearer to the center of the drill and increase gradually and progressively in width toward their sides farther from the center of the drill.

2. The method of making a twist drill which consists in providing a drill blank having U-shaped grooves extending lengthwise of the flutes of its blades and intersecting the cutting lips of the blades, and then twisting the blank so as to impart the desired spiral form to the blades and simultaneously effect a resulting change in the shape of the grooves.
- 10 3. The method of making a twist drill each of the cutting lips of which is provided with a plurality of cutting edges, which consists in forming the blades of the drill before they are twisted with grooves of 15 half-round form which extend through said cutting edges, and then bending the blades to the desired twist and simultaneously distorting the grooves from half-round to a resulting form.
- 20 4. The method of making a twist drill each of the cutting lips of which is provided with a plurality of cutting edges, which consists in forming the blades of the drill before they are twisted with U-shaped 25 grooves which extend through said cutting edges, and then bending the blades to the desired twist and simultaneously distorting the grooves from U-shape to semi-elliptical form.
- 30 5. The method of making a twist drill each of the cutting lips of which is provided with a plurality of cutting edges, which consists in forming the blades of the drill before they are twisted with grooves 35 of half-round form which extend through said cutting edges, and then bending the blades to the desired twist and simultaneously distorting the grooves from half-round to semi-elliptical form.
- 40 6. The method of making a twist drill each of the cutting lips of which is provided with a plurality of cutting edges,

which consists in providing a drill blank having longitudinal grooves of U-form in its flutes and extending through their cutting edges, the groove of one flute being arranged at a greater distance from the drill center than the groove of the other flute, and then twisting the blank to complete the drill and simultaneously change the form of 50 each groove from U-form to substantially semi-elliptical form.

7. The method of making a twist drill, each of the cutting lips of which is provided with a plurality of cutting edges, which consists in providing a drill blank having longitudinal U-shaped grooves in its flutes and intersecting its cutting edges, one of said grooves being deeper than the other and arranged at a greater distance 60 from the drill center, and then twisting the blank to complete the drill and simultaneously change the shape of each groove from U-form to substantially semi-elliptical 65 form.

8. The method of making a twist drill which consists in taking a suitable drill blank having fluted blades and forming the blades of the drill blank, before said blank is twisted, with longitudinal grooves of 70 substantially U-shape in cross-section and intersecting the cutting lips of the blades, and then twisting the drill blank so as to impart the desired spiral form to the blades and to simultaneously distort the grooves 75 from a substantially U-form to a form in which each groove is substantially semi-elliptical and shaped so as to produce at its outer edge an inwardly projecting undercut cutter which overhangs the deeper end 80 of the groove.

In testimony whereof I affix my signature.

NORMAN E. WOODS.
